RAILWAY SIGNALING

Paul H. Crago, Wilkinsburg, Pa., assignor to The
Union Switch & Signal Company, Swissvale,
Pa., a corporation of Pennsylvania

Application September 18, 1936, Serial No. 101,469

12 Claims. (Cl. 246—46)

My invention relates to railway signaling, and particularly to signaling involving wayside signals located along a trackway for governing the passage of trains.

5 A feature of my invention is the provision of novel and improved apparatus for establishing a distinctive control for each of three sections in the rear of an occupied section. Each distinctive control is effective to cause a corresponding aspect of the associated wayside signal whereby there is produced a three-block, four-indication, system of signaling.

10 The present invention is an improvement on the apparatus disclosed and claimed in an application, Serial No. 101,467, for Letters Patent of the United States, filed September 18, 1936, by Howard A. Thompson, for Railway signaling, as well as on the apparatus disclosed and claimed in an application, Serial No. 101,468, for Letters Patent of the United States, filed September 18, 20 15 20 1936, by Ralph R. Kemmerer, for Railway signaling.

25 I will describe two forms of apparatus embodying my invention, and will then point out the novel features thereof in claims.

30 In the accompanying drawings, Figs. 1A and 1B are diagrammatic views which when placed end to end in the order named illustrate one form of apparatus embodying my invention. Fig. 2 is a diagrammatic view illustrating a modification of a portion of the apparatus shown in Fig. 1A and also embodying my invention.

35 Similar reference characters refer to similar parts in each of the several views.

40 Referring to the drawings, the reference characters 1 and 2 designate the rails of a stretch of railway of track sections W—X, X—Y, and Y—Z.

45 As here shown, each track section is divided by insulated joints 9 into at least two subsections 1T, 2T, 3T, 4T, etc. Each subsection is provided with a track circuit which includes a track battery 10 connected across the rails at one end of the subsection and a track relay, designated by the reference character TR with a prefix the same as the numerical prefix in the reference character of the associated subsection, 50 connected across the rails at the other end of the subsection.

55 To govern the passage of trains through the stretch of railway, a wayside signal, designated by a suitable distinguishing reference character, is provided for each track section. Each of

these signals includes an upper unit U and a lower unit L. These units may take any one of several forms of signal mechanism such as semaphore, color light, searchlight, or position light. As here shown, each upper unit U is a semaphore 5 arm capable of assuming a horizontal or "stop" position, a 45° or "caution" position, and a vertical or "proceed" position; and each lower unit L is a caution lamp Y capable of displaying a yellow light.

10 Operatively connected with each semaphore arm U are contacts 17, 18, 19, 20, 21, and 22. Contact 17 is in engagement with contact 23 whenever the semaphore arm U is in the 30° position or the 89° position or at any point between these positions. Contacts 18, 19, and 21 are in engagement with contacts 24, 25, and 26, respectively, whenever the semaphore arm is in its 60° position or in its vertical position or at any point between these two positions, and are 15 in engagement with contacts 27, 28, and 29, respectively, whenever the semaphore arm is at any point below the 60° position. Contact 20 is in engagement with contact 30 whenever the semaphore arm is in its 60° or in its vertical position or at any point between these two positions. Contact 22 is in engagement with contact 31 whenever the semaphore arm is in its 43° position or in its vertical position or at any point between these two positions and is in engagement with contact 32 whenever the semaphore 20 25 30 35 arm is below the 43° position.

Each semaphore arm U is provided with a lamp E which when lighted provides supplementary color light indications corresponding to the 35 positions of the associated semaphore arm.

For controlling the associated signal, each section is provided with a polarized signal control relay, a neutral signal control relay, and an auxiliary relay designated by the reference characters DR, HR, and DP, respectively, each with a prefix the same as the reference character of the associated signal.

For controlling the associated relays DR and HR, each section is provided with a pair of conductors each of which extends to the signal next in advance and each of which includes a front contact of each of the associated track relays.

Each section is provided with an operating battery the terminals of which are designated by 50 the reference characters BO and CO and each section is provided with a line battery designated by the reference character 11. Each line battery 11 is provided with a low voltage positive terminal, a high voltage positive terminal, and 55

a common return terminal designated by the reference characters B1, B2, and C, respectively.

Each relay DR is connected to the associated pair of conductors by signal contact 17-23 of the associated signal. Each relay HR is connected to the associated pair of conductors through a back contact 16 of the associated relay DP and contact 18-27 of the associated signal. Each relay DP is governed by the associated relay DR. For example, relay 12DP is governed by a circuit which includes front contact 34 of relay 12DR, so that relay 12DP will be energized or deenergized when relay 12DR is energized or deenergized. As will be explained more in detail hereinafter, the pair of conductors for each section is at times supplied with energy of a relatively low value and at other times is supplied with energy of a relatively high value. The pickup value of the relays HR is such that these relays will become picked up upon receiving energy of the higher value.

25 The signal contacts 20, 21, and 22 and the relays HR and DP control the magnitude and direction of the energy supplied to the line conductors for the section next in the rear.

For controlling the signal lamps E and Y, each section is provided with an approach lighting relay designated by the reference character ER with a prefix the same as the reference character of the associated signal. The relays ER are connected in series with the line conductors for the section next in rear and therefore are energized at all times except when that line circuit is open. That is, the approach lighting relays ER become released to energize the associated lamp E and the control circuit for the associated lamp Y only when the section immediately to the rear of the signal with which such lamps are associated becomes occupied by a train.

The relays HR, DR, and DP control the upper unit U and the lower unit L of the associated signal in the following manner: When all relays are deenergized (see signal 15), both semaphore arm U and lamp Y are deenergized so that signal 15 is displaying its semaphore arm in the horizontal position to indicate "stop". When only the relay HR is energized (see signal 14), a caution circuit for the semaphore arm U of that signal is closed over a path which passes from terminal BO over front contact 35 of relay 14HR, semaphore arm U, and contact 19-28 of signal 14 to terminal CO. Semaphore arm U of signal 14 therefore is in the caution position to indicate "approach next signal prepared to stop". When relay DR is energized in the reverse direction (see signal 13), relay 13DP is energized over front contact 34 of relay 13DR so that relay 13HR becomes deenergized and so that another caution circuit for semaphore arm U is closed over front contact 36 of relay 13DP. A circuit also is established for the lamp Y of the lower unit L of that signal. This circuit passes from terminal BO over front point of contact 36 of relay 13DP, front point of contact 37 of relay 13DR, reverse polar contact 38-39 of relay 13DR, lamp Y, and back contact 41 of relay 13ER to terminal CO. Signal 13, therefore, is displaying its upper semaphore arm U in the caution position and a circuit for lamp Y is established so that when relay 13ER becomes released by a train approaching signal 13 in section W-X, this signal will display its semaphore arm in the caution position over a yellow light

to indicate "approach next signal at medium speed". When relay DR becomes energized in the normal direction (see signal 12 and assume for the moment that its semaphore arm U is in the caution position), relay 12DP will also be energized so that the caution circuit for the upper semaphore arm U will remain closed over front contact 36 of relay DP and a proceed circuit for the semaphore arm U will be closed over a path which passes from terminal BO over front contact 36 of relay 12DP, front point of contact 42 of relay 12DR, normal polar contact 38-40 of relay 12DR, semaphore arm U, and contact 19-28 of signal 12 to terminal CO. When the semaphore arm U reaches its 60° position, contact 19-28 will become opened and contact 19-25 will become closed so that the proceed circuit will then include the front point of contact 43 of relay 12DP. Signal 12 will, therefore, display its semaphore arm in the vertical position, as shown in the drawings, to indicate "proceed at normal speed". When the semaphore arm U of signal 12 attained its proceed position, signal contact 17-23 became opened so that relay 12DR and consequently relay 12DP are both released. The caution and clear circuits for upper semaphore arm U, therefore, are disconnected from the terminals BO and CO of the operating battery and are connected directly to the line conductors for the section W-X. The path connecting the proceed circuit to the line conductors for section W-X includes back point of contact 42 of relay 12DR, back point of contact 44 of relay 12HR, back point of contact 36 of relay 12DP, signal contact 18-24, as well as back point of contact 43 of relay 12DP and signal contact 19-25.

As here shown, a train K is indicated diagrammatically in the section immediately to the right of location Z so that the signal 15 and associated relays are all deenergized.

When signal 15 and associated apparatus is in this condition, relay 14HR is energized in the reverse direction by energy of a relatively low value over a path which passes from terminal B1 of battery 11 at signal 15, through signal contact 22-32 of signal 15, front contact 45 of relay 6TR, front contact 46 of relay 5TR, relay 14HR, back contact 16 of relay 14DP, contact 18-27 of signal 14, front contact 47 of relay 5TR, front contact 48 of relay 6TR, back point of contact 49 of relay 15DP, signal contact 21-29 of signal 15, and relay 15ER to terminal C.

When relay 14HR is energized so that semaphore arm U of signal 14 is in the caution position, relay 13DR is energized in the reverse direction by energy of relatively high value over a path which passes from terminal B2 of battery 11 at signal 14, through front contact 50 of relay 14HR, back point of contact 51 of relay 14DP, contact 22-31 of signal 14, front contact 52 of relay 4TR, front contact 53 of relay 3TR, relay 13DR, contact 17-23 of signal 13, front contact 54 of relay 3TR, front contact 55 of relay 4TR, back point of contact 56 of relay 14DP, contact 21-29 of signal 14, and relay 14ER to terminal C.

When relay 13DR is energized in the reverse direction, semaphore arm U remains in its caution position, relay 13DP becomes energized and relay 13HR becomes deenergized. When signal 13 and associated apparatus is in this condition and assuming for the moment that semaphore arm U of signal 12 is in the caution position, relay 12DR will be energized in the normal direction by energy of relatively high value over a

path which passes from terminal B2 of battery 11 at signal 13, through front point of contact 57 of relay 13DP, front contact 58 of relay 2TR, front contact 59 of relay 1TR, contact 17-23 of signal 12, relay 12DR, front contact 60 of relay 1TR, front contact 61 of relay 2TR, contact 22-31 of signal 13, front point of contact 62 of relay 13DP, and relay 14ER to terminal C.

As a result semaphore arm U of signal 12 is caused to assume the "proceed" position, so that the line conductors for the section next in rear of location W are supplied with energy of the high value in the normal direction over contacts 20-39, 22-31, and 21-26 of signal 12. Consequently, the signal (not shown) associated with such conductors in the rear will be in position to display the normal proceed indication.

Summing up then for the system illustrated in Figs. 1A and 1B, it will be seen that, when a block is occupied by a train, the signal for that block will display its semaphore arm in the horizontal position to indicate "stop"; the signal for the section first in rear of such occupied section will display its semaphore arm in the 45° position to indicate "approach next signal prepared to stop"; the signal for the section second in rear of such occupied section will display its semaphore arm in the 45° position over a yellow light to indicate "approach next signal at medium speed"; and the signal for the section third in rear of such occupied section will display its semaphore arm in the vertical position to indicate "proceed at normal speed".

The relays DP are provided with a slow releasing characteristic so that the caution circuit for the associated semaphore arm U will remain closed and so that the energization of the line conductors to the rear will not be disturbed during pole changing periods. For example, when the train K vacates the section to the right of the location Z so that the energization of relay 13DR is changed from the reverse direction to the normal direction to cause signal 13 to display the normal proceed indication, front contact 34 of relay 13DR will become momentarily opened. Due to the slow release characteristic of relay 13DP, however, front points of contacts 38, 57, and 62 of this relay remain closed so that the energization of the circuits controlled by these contacts will not be disturbed during this period.

The relays HR are provided with a slow release characteristic so that both the caution circuit for the associated semaphore arm U and the circuit for the line conductors in the rear will remain closed during the open circuit periods when contact 22 for the signal in advance is moving from contact 32 to contact 31. For example, when the train K vacates the section to the right of location Z so that relay 15HR becomes energized to cause semaphore arm U of signal 15 to assume the 45° position to indicate "approach next signal prepared to stop", contact 22 will become disengaged from contact 32 and will become engaged to contact 31 to supply energy of high value to relay 14DR. Due to the slow release characteristic of relay 14HR, however, front point of contact 35 and front contact 53 of this relay will remain closed during the time that contact 22 is in engagement with neither contact 32 nor 31 so that the energization of the circuits controlled by these contacts will not be disturbed during such open circuit periods.

When the energization of the line conductors is changed from the high value to the low value to provide a more restrictive indication, such line

conductors are momentarily disconnected from the source of energy so that the associated relay DR will be certain to release. For example, if the section Y-Z becomes occupied by the train K so that the energization of the line conductors for the section X-Y is changed from the high value to the low value, front contact 50 of relay 14HR will become opened to disconnect energy from the line conductors for the section X-Y and such line conductors will remain deenergized until such time as the semaphore arm U of signal 14 drops below its 45° position.

Under this condition, that is, with section Y-Z occupied either by a train making a reverse move or by a train entering section Y-Z from a spur track (not shown), relay 13DR will become released so that the circuit for the caution lamp Y of signal 13 cannot be established. A short time thereafter, relay 13DP will become released so that relay 13HR will become energized over the line conductors for section X-Y to maintain the energization of the caution circuit for semaphore arm U of signal 13. Upon the releasing of relay 13DP and the picking up of relay 13HR, the line conductors for section W-X will be supplied with energy of high value in the reverse direction so that semaphore arm U for signal 12, which is being energized in the normal direction by the line conductors for section W-X, will become released. The releasing of semaphore arm U for signal 12 will cause contact 17-23 of that signal to become closed so that relay 12DR will become energized in the reverse direction. This energization of relay 12DR will cause relay 12DP to become energized so that both the caution circuit for semaphore arm U of signal 12 and a circuit for lamp Y of signal 12 will become established. When semaphore arm U reaches its 45° position, it will be held in that position by the caution circuit so that signal 12 will be in condition to indicate "approach next signal at medium speed" to an approaching train. The energization of the line circuit to the rear of location W will not be disturbed, since relay 12DP will become energized to close its front contacts to supply energy of the high value in the normal direction to such rear line circuit before semaphore arm U of signal 12 reaches its 60° position to open signal contacts 20-39 and 21-26. It will be seen, therefore, that tumble-down of the signal control circuits to the rear will be avoided even though a section becomes occupied by a train moving in the reverse direction or by a train from a spur track.

Referring now to Fig. 2, I have shown herein one signal and associated apparatus which, when included in a system with wires 70 and 71 at the right connected with wires 72 and 73, respectively, at the left, will provide a three-block, four-indication system similar to that described for the system illustrated in Figs. 1A and 1B.

The principal difference between the apparatus illustrated in Fig. 2 and that illustrated in Figs. 1A and 1B is that in the latter the semaphore arm U, when in the normal proceed position, is directly connected to the line conductors for the forward section, whereas in Fig. 2, the semaphore arm never receives energy from the line conductors.

Semaphore arm U is provided with a contact 74-75 which is closed at all times except when the semaphore arm is in the vertical or "proceed" position, and with a contact 76-77 which is closed whenever the semaphore arm is in the 30° position or vertical position or at any point 75

between these two positions, as well as with contacts 78 and 79 which are in engagement with contacts 80 and 81, respectively, when the semaphore arm is in the 43° position or in the vertical position or at any point between these two positions, and are in engagement with contacts 82 and 83, respectively, when the semaphore arm is at any point below the 43° position.

Relay DR is connected to the conductors for the forward section over contact 76-77 and relay DP is controlled by front contact 84 of relay DR. Relay HR is connected to the line conductors for the forward section over back contact 85 of relay DP so that, when relay DP is energized, relay HR will be deenergized to conserve energy as well as to avoid the possibility that the winding of relay HR might act as a shunt path across relay DR thereby decreasing its release time. A resistor 86 is provided for limiting the current flowing in the relay DR and a shunt path, including signal contact 74-75 is provided around resistor 86 so that whenever the semaphore arm U is in a position other than the normal proceed position the relay DR will receive its normal current but, when the semaphore arm U is in the proceed position, relay DR will receive a reduced current which will insure a more positive release of this relay when the energization of the line conductors is changed from the high value to the low value.

The relays DR, DP and HR control the semaphore arm U and lamp Y in the following manner: When relay HR is energized, a caution circuit for semaphore arm U becomes closed over front contact 87 of relay HR so that the semaphore arm is caused to assume the 45° position to indicate "approach next signal prepared to stop". When relay DR becomes energized in the reverse direction, relay DP also becomes energized to close another caution circuit for the semaphore arm and to establish a circuit for the lamp Y so that, when relay DR becomes released to close back contact 93, the signal will display the semaphore arm in the 45° position over a yellow light to indicate "approach next signal at medium speed". The caution circuit for the semaphore arm includes front contact 88 of the relay DP and the circuit for lamp Y includes front contact 88 of relay DP as well as front contact 89 and reverse polar contact 90-91 both of relay DR. When relay DR is energized in the normal direction, relay DP, of course, remains energized so that the caution circuit remains closed and a proceed circuit is closed to cause the semaphore arm U to assume the vertical position to indicate "proceed at normal speed". The proceed circuit includes front contact 88 of relay DP as well as front contact 89 and normal polar contact 90-92 both of relay DR.

The magnitude and direction of the energy supplied to the conductors for the rear section is controlled by the relays DP and HR and contacts 78 and 79 in the following manner: When the semaphore arm is in its horizontal or "stop" position, the line conductors for the rear section are connected in the reverse direction with terminals B1 and C of battery 11 through signal contacts 78-82 and 79-83. When the relay HR is energized and the semaphore arm is in the 45° position, the line conductors for the rear section are connected in the reverse direction to terminals B2 and C of battery 11 over front contact 94 of relay HR, back points of contacts 95 and 96 of relay DP and signal contacts 78-80 and 79-81. When the relay DR is energized so that

the relay DP is energized, the line conductors for the rear section are connected in the normal direction to terminals B2 and C of battery 11 through front points of contacts 95 and 96 of relay DP and signal contacts 78-80 and 79-81. The line conductors for the rear section, therefore, are supplied with energy of relatively low value in the reverse direction when the signal and associated apparatus is in condition to indicate "stop", or with energy of relatively high value in the reverse direction when the signal and associated apparatus is in condition to indicate "approach next signal prepared to stop", or with energy of relatively high value in the normal direction when the signal and associated apparatus is in condition to indicate either "approach next signal at medium speed" or "proceed at normal speed".

Although I have herein shown and described only a few forms of apparatus embodying my invention, it is understood that various changes and modifications may be made therein within the scope of the appended claims without departing from the spirit and scope of my invention.

Having thus described my invention, what I claim is:

1. In combination, a section of railway track, a pair of conductors for said section, means for supplying said conductors with energy of a particular magnitude or with energy of a higher magnitude in one direction or with energy of said higher magnitude in the other direction in accordance with traffic conditions in advance of said section, a neutral relay responsive to energy of said particular magnitude receiving current from said conductors, a polarized relay responsive only to energy of said greater magnitude also receiving current from said conductors, and traffic governing means for said section controlled by said two relays.

2. In combination, a section of railway track, a pair of conductors for said section, means for supplying said pair of conductors with energy of a relatively low value or with energy of relatively high value in the reverse direction or with energy of said relatively high value in the normal direction in accordance with traffic conditions in advance of said section, a neutral relay responsive to energy of said low value receiving current from said conductors, a polarized relay responsive only to energy of said high value also receiving current from said conductors, and a signal for said section caused to indicate "approach" when said neutral relay is energized or to assume a condition to indicate "approach medium" when said polarized relay is energized in the reverse direction or to indicate "proceed" when said polarized relay is energized in the normal direction.

3. In combination, a section of railway track, a pair of conductors for said section, means for supplying said pair of conductors with energy of a relatively low value or with energy of relatively high value in the reverse direction or with energy of said relatively high value in the normal direction in accordance with traffic conditions in advance of said section, a neutral relay responsive to energy of said low value receiving current from said conductors, a polarized relay responsive only to energy of said high value also receiving current from said conductors, an auxiliary relay which becomes energized or deenergized according as said polarized relay is energized or deenergized, a signal for said section including a first indication unit and a second in-

dication unit, said first indication unit being a semaphore arm capable of assuming a stop and a caution as well as a proceed position and said second indication unit being a lamp, a caution 5 circuit for said semaphore arm including a front contact of said neutral relay, another caution circuit for said semaphore arm including a front contact of said auxiliary relay, a proceed circuit for said semaphore arm including a front contact of said auxiliary relay as well as a front neutral contact and a reverse 10 contact of said auxiliary relay and a circuit for said lamp including a front contact of said auxiliary relay as well as a front neutral contact and a reverse 15 polar contact both of said polarized relay.

4. In combination, a forward and a rear section of railway track, a neutral relay and a polarized relay for said forward section, means effective when the forward section is unoccupied 20 to energize only said neutral relay or only said polarized relay in one direction or only said polarized relay in the other direction in accordance with traffic conditions in advance of said forward section, a pair of conductors for the rear section, means effective to supply said conductors with energy of a relatively low value when both said relays are deenergized, means effective to supply said conductors with energy of relatively high value in one direction when said neutral relay 25 only is energized, means effective to supply said conductors with energy of said relatively high value in the other direction when said polarized relay is energized in either direction, and traffic governing means for the rear section receiving 30 energy from said pair of conductors and selectively responsive to the value and direction of the current received therefrom.

5. In combination, a forward and a rear section of railway track, a neutral relay and a polarized relay for said forward section, means effective when the forward section is unoccupied to energize only said neutral relay or only said polarized relay in one direction or only said polarized relay in the other direction in accordance 40 with traffic conditions in advance of said forward section, a repeating relay which becomes energized or deenergized according as said polarized relay is energized or deenergized, a signal for said section caused to display a proceed indication when either said repeating relay or said neutral relay is energized, a pair of conductors for the rear section, means effective to supply said conductors with energy of a relatively low value when said signal is in condition to indicate stop, 45 means effective to supply said conductors with energy of a relatively high value in the reverse direction when said neutral relay is energized provided said repeating relay is deenergized and said signal is in condition to display said proceed indication, and means effective to supply said conductors with energy of said relatively high value in the normal direction when said repeating relay is energized provided said signal is in condition to display said proceed indication. 50

6. In combination, a forward and a rear section of railway track, a neutral relay and a polarized relay for said forward section, means effective when the forward section is unoccupied to energize only said neutral relay or only said polarized relay in one direction or only said polarized relay in the other direction in accordance with traffic conditions in advance of said forward section, a repeating relay which becomes energized or deenergized according as said polarized relay is energized or deenergized, a signal 65

for said section caused to display a proceed indication when either said repeating relay or said neutral relay is energized, a pair of conductors for the rear section, a first contact and a second contact both of which are closed when said signal 5 is displaying a stop indication and a third contact which is closed when said signal is displaying said proceed indication, a pair of line conductors for the rear section, a source of energy having a low voltage terminal and a high voltage terminal, 10 means including said first contact and said second contact as well as a back contact of said repeating relay for connecting said conductors to said low voltage terminal, means including said third contact and a front contact of said 15 neutral relay as well as a back contact of said repeating relay for connecting said conductors to said high voltage terminal in one direction, and means including said third contact and a front contact of said repeating relay for connecting 20 said conductors to said high voltage terminal in the other direction.

7. In combination, a stretch of railway track divided into sections, a pair of conductors for each section, means effective when one section is occupied to supply the conductors for the section next in rear of such occupied section with energy of a particular magnitude, means then effective to supply the conductors for the section second in rear of such occupied section with energy of 25 30 a different magnitude in one direction, means then effective to supply the conductors for the section third in rear of such occupied section with energy of said different magnitude in the other direction, and traffic governing means for each 35 section selectively responsive to the direction and magnitude of the energy supplied to the associated conductors.

8. In combination, a stretch of railway track divided into sections, a pair of conductors for 40 each section, means effective when one section is occupied to supply the conductors for the section next in rear of such occupied section with energy of a relatively low value in one direction, means then effective to supply the conductors for the 45 section second in rear of such occupied section with energy of a relatively high value in said one direction, means then effective to supply the conductors for the section third in rear of such occupied section with energy of said relatively high 50 value in the other direction, and traffic governing means for each section selectively responsive to the direction and value of the energy supplied to the associated conductors.

9. In combination, a section of railway track, 55 a pair of conductors for said section, a first signal control relay and a second signal control relay, both receiving energy from said pair of conductors, means including said pair of conductors effective when said section is unoccupied to energize said first signal control relay or to energize said second signal control relay in accordance with traffic conditions in advance of said section, a signal for said section governed by said two relays and caused to assume one condition 60 65 when said first signal control relay is energized or another condition when said second signal control relay is energized, means effective to deenergize said first signal control relay when said second signal control relay is energized, means effective to deenergize said second signal control relay when said signal is in such other condition, and means including a back contact of each of said two relays for then connecting said signal direct to said pair of conductors. 70 75

10. In combination, a section of railway track, a pair of conductors for said section, a first signal control relay and a second signal control relay both receiving energy from said pair of conductors, means including said pair of conductors effective when said section is unoccupied to energize said first signal control relay or to energize said second signal control relay in accordance with traffic conditions in advance 10 of said section, a signal for said section governed by said two relays and caused to assume one condition when said first signal control relay is energized or another condition when said second signal control relay is energized, means effective 15 to deenergize said first signal control relay when said second signal control relay is energized, means effective to deenergize said second signal control relay when said signal is in such other condition, and means including a contact oper- 20 ably governed by said signal as well as a back contact of said first signal control relay and a back contact of said second signal control relay for then connecting said signal to said pair of conductors.
- 25 11. A railway signal system comprising a stretch of railway track divided into sections, a pair of line conductors for each section, means for each section for supplying the conductors for the section next in rear with energy of relatively 30 low value in one direction or with energy of rela-

tively high value in the same direction or with energy of said high value in the other direction in accordance with traffic conditions in advance, a neutral relay for each section responsive to energy of said low value receiving current from the 5 associated conductors, a polarized relay for each section responsive only to energy of said high value also receiving current from the associated conductors, and traffic governing means for each section controlled by the associated neutral and 10 polarized relays.

12. A railway signal system comprising a stretch of railway track divided into sections, a pair of line conductors for each section, means for each section for supplying the conductors for 15 the section next in rear with energy of relatively low value in one direction or with energy of relatively high value in the same direction or with energy of said high value in the other direction in accordance with traffic conditions in advance, 20 a neutral relay for each section responsive to energy of said low value receiving current from the associated conductors, a polarized relay for each section responsive only to energy of said high value also receiving current from the associated 25 conductors, and a signal for each section governed by the associated relays, each said signal being capable of displaying at least three different proceed indications.
